DESIGN FOR A PLATE DEVELOPER

James T. Campbell, Detroit, Mich.

Application October 31, 1945, Serial No. 123,345

Term of patent 14 years

(Cl. D61—1)

To all whom it may concern:

Be it known that I, James T. Campbell, a citizen of the United States, residing at Detroit, in the county of Wayne and State of Michigan, have invented a new, original, and ornamental Design for a Plate Developer, for which the following is a specification, reference being had to the accompanying drawing, forming part thereof, in which the figure is a perspective view of the plate developer, showing my design.

The ends of the plate developer are plain and the opposite side presents substantially the same appearance as the side shown.

I claim:

The ornamental design for a plate developer, substantially as shown and described.

JAMES T. CAMPBELL.
